Fig. 2

Fig. 1

Fig. 3

FIGURE 1 is an elevational view of a container for oil products or the like showing my new design;

FIGURE 2 is a top view thereof; and

FIGURE 3 is a bottom view thereof.

The characteristic features of my design reside in the portions shown in full lines and specifically in the combination of three single spaced-apart ribs around the columnar periphery of a container having the configuration shown.

I claim:

The ornamental design for a container for oil products or the like, as shown and described.
